ATTORNEYS.

UNITED STATES PATENT OFFICE

124,872

DESIGN FOR A BADGE OR THE LIKE

Miles S. Phillips, Cleveland, Ohio, assignor to
The Lake Erie Steel and Blanking Company,
Cleveland, Ohio, a corporation of Ohio

Application December 6, 1940, Serial No. 97,122

Term of patent 7 years

To whom it may concern:

Be it known that I, Miles S. Phillips, a citizen of the United States, residing at Cleveland, county of Cuyahoga, and State of Ohio, have invented a new, original, and ornamental Design for a Badge or the like, of which the following is a specification, reference being had to the accompanying drawing, forming a part thereof.

In the drawing, Fig. 1 is a front view of the badge embodying my new design; Fig. 2 is a side view of Fig. 1.

I claim:

The ornamental design for a badge or the like, as shown.

MILES S. PHILLIPS.
